UNITED STATES PATENT OFFICE.

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY.

BLANK CUTTING AND ASSEMBLING MACHINE.

Application filed August 18, 1920. Serial No. 404,409.

This invention relates to machines for cutting sheet material into blanks and assembling the latter to form composite articles.

It is common practice in the manufacture of heels for cheap and moderately-priced lines of shoes to utilize waste or scrap leather for one or for several of the lifts of a heel. Each lift made up of two or more pieces of leather is called a pieced lift, and such a lift secured to another or others of similar make or to a one-piece lift constitutes a heel section. According to one well-known method of making heels, a heel section of the kind described is assembled with a top lift of a good grade of leather and with a lift of leather or fiberboard at the heel seat surface of the heel, the lifts and heel section being secured together and compressed to produce a heel that is relatively cheap, yet durable, and susceptible of a high polish and of a fine finished appearance. Heretofore the manufacture of pieced-lift heel sections has involved an immense amount of manual labor and slow and tedious operations. For these reasons also the labor obtainable for heel building is often of a relatively low grade, indifferent, and inefficient. Under such conditions, material is seldom utilized to the best advantage and many defective heels are produced.

It is an object of this invention to provide a machine for cutting leather scrap into pieces of predetermined shapes and assembling them to produce pieced lifts. Preferably a pieced lift is secured in superposed relation upon another or other pieced lifts or upon a one-piece lift to make a heel section, through the operation of means embodied in the machine and conveniently automatically operative for the purpose described.

In one aspect the invention comprises means for cutting sheet material into pieces of different shapes bearing a predetermined relation to each other and assembling them to make a complete article.

As shown, the contour lines of the lift sections, which coincide with or, more correctly, constitute the peripheral edges of the complete lift, are produced by a heel lift die preferably under the control of the operator, while a plurality of cutters, preferably automatically operated, complete the shaping of the sections. In a preferred construction the

material to be cut is supported on a table which co-operates with and controls a plurality of cutters so that the latter operate to produce lift sections of different shapes in a predetermined order, conveniently, in such an order that the sections taken as they arrive at the assembling means fit together and produce complete lifts.

Since many of the pieces of scrap utilized for lift sections are wrinkled, bent, or corrugated, it is necessary to provide means for flattening the pieces prior to the first cutting operation and for holding the pieces in flattened or extended condition during all subsequent shaping of the pieces. Such flattening and holding means must be so located as not to interfere with the cutters. In the illustrative machine the flattening means is operative through the die, and the holding means through the support for the pieces, one embodiment of the holding means comprising relatively slender pins which enter the pieces of leather from below and maintain them in extended or flattened condition on the support.

As shown, the table carries a plurality of cutting blocks upon which the work is placed by the operator. And in order that the stock may be utilized to the best advantage, an indicator or, broadly speaking, a gage, is associated with each block so that the operator may tell at a glance the size and shape of the blank which will be cut from the piece of material placed on any given block. Conveniently the means for holding the pieces of work flat and in extended condition on the cutting blocks are so constructed and arranged as to serve as gages, the perforations in the blocks, through which the pins or work-penetrating members of the holding means pass, being arranged in groups to outline the shape and show approximately the size of the various blanks which will be cut on the blocks.

Another feature of greatest importance resides in the assembling means which takes the lift sections from the support where they were cut and assembles them accurately into lifts. Not only are the sections properly positioned relatively to each other to produce perfect lifts but the edges of the sections are closely abutted and maintained in such relation during the application of the securing means.

Preferably the assembling means co-operates with a cementing means in such a manner that the lifts for a heel or a heel section are secured to each other while in the assembler. Subsequently the assembled and attached lifts are forced into a holder where, as heels or heel sections, they have time to dry while under pressure.

Means is provided by which the assembler 10 automatically discharges the assembled and attached lifts into said holder when they have been built up to a definite thickness, the construction and arrangement being preferably such that heels or heel sections of 15 various predetermined thicknesses may be produced by the assembler and passed on to the holder.

In order that the heels or heel sections in 20 the holder may be distinct and unattached, no cement is applied to the bottom of the last lift assembled in the assembling means. For the same reason no cement is applied to the top face of the first lift which enters the assembler. In other words, cement is applied 25 to the opposed faces only of the lifts as a result of a novel and highly efficient construction and arrangement of the assembling and cementing means.

In the illustrative machine, the operator 30 works at only one station where the pieces of leather or other material are placed upon a work supporting surface on a rotatable table which is conveniently automatically turned to carry the work to the other cutting instrumentalities and to present at regularly recurring intervals the work supporting surfaces in front of the operator. Preferably the cutter in front of the operator is a die which imparts the permanent part of the 35 outline to the lift section or other blank. Furthermore, this die, which is normally out of operative relation to the work supporting surface so that work may be positioned with ease and dispatch, is movable to operative 40 position under manual control of the operator. By reason of this arrangement all danger of injury to the operator's fingers is obviated since the latter must be removed from the field of operations during the lateral movement of the die to operative position. As shown, continued movement in the 45 same direction of the manually movable controlling member for the die initiates power operation of the machine.

50 A further feature of importance relates to the connections of the cutters to the power operating means, a clutching means being interposed between each individual cutter and said power means whereby the timing and the order of operation of the cutters can be determined with precision. Preferably 55 control of the cutters, with the exception of the die, is exercised by means carried by the rotatable table which supports the work.

In the operation of the illustrative ma-

chine, the work is placed in a position selected by the skilled operator and there it remains throughout all the succeeding cutting operations. Heretofore the operator was compelled to position the stock for each of 70 the two, and oftentimes three, cutting operations on each piece of stock. There is evidently a marked saving of time and of energy for the operator in the use of applicant's invention. Moreover, the operator 75 now deals directly with only one cutter or die, whereas in the past, work had to be positioned with respect to at least two cutters, and according to one method still practiced, twelve to twenty dies are used. The result 80 is a lessening of danger to the operator, an advantage of no inconsiderable importance. Other advantages of the invention relate to the excellence and uniformity of the product 85 of the machine.

While the illustrative machine is constructed for the purpose specifically of cutting leather scrap material into lifts and lift sections, it is to be understood that various 90 important features of the invention may have other and independent applications and uses.

Other features of construction and combinations of parts will be described in the following detailed description and pointed out 95 in the appended claims.

In the drawings:

Fig. 1 is a plan view from above of the illustrative machine;

Fig. 2 is a plan view of the table and part 100 of the operating means therefor;

Fig. 3 is a view in side elevation and partly in section with parts omitted to show the operating mechanism for the table and the die cutter with its operating mechanism;

Fig. 4 is a front view of the die cutter with its immediate operating means;

Fig. 5 is a view in side elevation of one of the knife cutters with its operating mechanism;

Fig. 6 is a front view of the knife cutter shown in Fig. 5;

Fig. 7 is a detail view of one of the adjusting means for the knife cutter;

Fig. 8 is a view in side elevation and partly in section of the mechanism for brushing the waste pieces from the table;

Fig. 9 is a view in side elevation and partly in section of the assembling means for the lifts, together with its operating 115 mechanism and showing its relation to the table;

Fig. 10 is a section of the holder for heels or heel sections;

Fig. 11 is a detail view of the pasting mechanism; and

Fig. 12 is a detail view of the upper end of the holder.

In the illustrative machine there is shown a table 14 mounted for rotation in the frame

of the machine and provided with a plurality of work supporting surfaces, the said surfaces being preferably in the form of cutting blocks 16 removably secured to the 5 table so as to be interchangeable, thus making provision for substituting cutting blocks of different patterns at various stations along the peripheral portion of the table. Inasmuch as the cutters which co-operate 10 with the cutting blocks 16 must come into initial contact with the blocks, the latter are preferably made of some relatively soft metal or metallic substance, such as brass. Mounted over the cutting bed is a plurality 15 of cutters indicated at 18, of which one is in the form of a die 20 (Figs. 3 and 4), the arrangement being such that the die co-operates with each and every one of the cutting blocks 16 while each of the remaining 20 cutters 18 co-operates with certain only of the blocks as will be hereinafter described. The operator stands at station A (Fig. 2) in front of the die 20 and places a piece of work upon each cutting block, especially 25 selected for said block, as each block passes before him during the rotation of the table. The die cuts out a blank from the piece of leather or other sheet material on the cutting block and, if the piece be large enough to 30 make a complete lift, it is placed only on the block shown in Fig. 2 at station H and no other cutter operates upon the blank thus formed. If, however, the blank formed by the die will make only part of a lift, one of 35 the cutters 18 is arranged to operate subsequently upon the same blank giving it a straight edge cut and making a lift section. Progressively with the cutting operations the table carries the lifts and lift sections 40 to station H where an assembler 22 (Fig. 1) collects the lifts and lift sections in proper superposed relation to make heels or heel sections. Between each pair of lifts thus assembled a layer of paste is applied as the 45 assembler passes over a cementing means 24 (Figs. 1 and 11) on the way back from a holder 26 (Figs. 1 and 9) in which the heels or heel sections are deposited by the assembler. Preferably the holder is of a 50 length to hold a considerable number of heels or heel sections built up of the lifts in the manner described so that by the time they reach the outlet at the lower end of the holder (Fig. 9), the cement has had time to 55 dry.

Referring to Figs. 3 and 4 of the drawings of the illustrative machine it will be observed that the die 20 is supported detachably, by means including a bolt 27, in a 60 carrier 28 pivoted at 30 upon a bracket 32 extending from the standard 34. According to the preferred construction the members 36, pivoted at 30, are constructed in the form of casings adapted to receive the ends 65 of the rods 38 which are adjustably secured in sleeves 40 extending from opposite sides of the carrier 28. Surrounding and yieldingly supporting the upper end of each rod 38 within the housing or casing 36 is a spring 40 shown in dotted lines in Fig. 3. 70 Carried by each rod 38 is a pin or stud 42 arranged to travel along a slot or cam path 44 in opposite sides of the bracket 32, the said cam path being so shaped that, as the die swings outwardly into position over the 75 block 16, the roll on the stud 42 moving along said path will cause the die to descend toward the cutting block until the said roll reaches the vertical part 46 of the slot or cam path 44, after which the die carrier is 80 forced vertically downwardly by power means to be described. As indicated in Fig. 3 of the drawings, one of the casing members 36 is provided with a projecting arm 48 along the upper edge of which there is arranged to travel a roll 50 mounted on a lever arm 52 pivoted at 54 on the bracket 32 and having a handle 56 (Fig. 1) in line with the axis of the roll 50, the arrangement being such that as the operator moves the 85 handle 56 away from the front of the machine, the roll 50 travels along the upper edge of the arm 48 and causes the die carrier to be moved about the pivot points 30 with the result, as before stated, that the die moves 90 forwardly and also downwardly toward the cutting block. Just as the roll on the stud 42 reaches the vertical portion 46 of the cam path 44, the adjustable member 58 (Fig. 3) mounted in the lever arm 52 comes into contact with one arm 60 of a bell crank, the other arm 62 of which has a segment rack connection with the upper end of a rod 64, the lower end of which has a similar connection with an arm 66 securely attached to 100 a shaft 68 which carries at its other end an arm 70 to which is connected a link 72 leading to a train of links and levers for actuating the clutch on the main shaft of the machine. It will be understood from the 105 foregoing description that as the roll 50 on the lever arm 52 reaches the end 74 of the arm 48, thus effectively locking the die in its extreme forward position with the roll on the stud 42 in the vertical slot 46, power operation of the machine begins, with the result that the die is forced downwardly in its operative stroke to die out a blank from the material resting on the cutting block. 110 In the construction shown, the die is forced downwardly in its operative stroke by a plunger 76 slidably mounted in a housing 78 at the front portion of the bracket 32, the plunger being arranged to contact with the upper surface of the die carrier 28 to force the latter downwardly. Upon retraction of the plunger the springs 40 return the die upwardly and backwardly to uncover the cutting block so that material may be positioned upon the block with 115 120 125 130

ease and dispatch in the free space thus provided.

The means for operating the die plunger 76 comprises preferably a shaft 80 (Figs. 3 and 4) and connections between the shaft and the plunger of a new and improved type which will now be described. Surrounding an eccentric 82 on the end of the shaft 80 is an eccentric strap 84 which is integral with a short pitman 86, a cap plate 88 being attached to the front end of the eccentric to hold the strap in place. Pivoted at 90 to the lower end of the pitman 86 is a link 92 pivoted at its other end at 94 to one end of the lever 96 secured to a short shaft 98 mounted in a bearing 100 (Fig. 1) secured to the upper surface of the bracket 32. Secured to the other end of the shaft 98 is a lever arm 102 having a projecting stud member 104 positioned in a fork 106 integral with or fixedly attached to a spider member 108 (Figs. 1 and 3) which does not rotate but which has an up and down motion through the operation of means hereinafter described. Referring again to Figs. 3 and 4, it will be seen that the link 92 is slidably secured in a tiltable bed member 110 pivoted at 113 in the upper end of the yoke member 112 fixed to the upper end of the plunger 76. It will be clear that, with the link 92 and the pitman 86 occupying the positions shown in Fig. 4, rotation of the eccentric 82 will result in the reciprocation of the plunger 76. If, however, the link 92 be moved to the left in Fig. 4 until the pivot point 94 reaches a point directly under the center of the shaft 80, in which case the pivot 90 will be positioned over to the left a distance equal to the space between the pivots 90 and 94, then rotation of the eccentric 82 will result in the reciprocation of the pitman 86 and an oscillation of the link 92 about the pivot point 94 without effecting movement of the plunger 76. For absorbing the rocking movement of the link 92 under the circumstances just described, there is provided, as above stated, the bed member 110 pivoted in the yoke 112 and oscillatable through a small arc, as indicated in said Fig. 4, during the rocking movement of the link 92. It will be clear from the construction just described that the shaft 80 with its eccentric 82 may continue to operate the pitman 86 without affecting the die operating plunger 76 so that the latter is operated only in properly timed relation to the other parts of the machine.

Since the die 20 wears more or less rapidly during use and has its height reduced by sharpening, it is both necessary and desirable to provide for an adjustment of the plunger 76. In the illustrative construction the yoke member 112 (Fig. 4) is integral with an eccentrically screw-threaded member 116 upon which is threaded a cylindri-

cal sleeve member 118. Entering the latter member from below is a solid cylinder 120 carrying integrally therewith a screw-threaded projection 122 which is adjustable in a screw-threaded socket in the member 116. To lengthen the plunger the cylinder 120 is turned counterclockwise and then the hollow cylinder 118 is turned downwardly until its lower end comes in firm contact with the flange on the head 124 of the cylinder 120, thus locking the latter member in its adjusted position and providing additional backing for the head 124 which constitutes the head of the plunger 76.

The other cutters 18 are mounted similarly to the die cutter upon other brackets 32 which are removably attached to the standard 34 by bolts, as shown at 130 (Fig. 5), the arrangement being such that a greater or less number of the cutters may be mounted on the standard for use in a given time or under a given set of circumstances. In the illustrative machine these cutters are shown as knife cutters 132 mounted adjustably between clamping plates 134 secured together by bolts 136 which pass through slots in the knife so that the latter may be adjustable vertically, when the clamping plates are loosened, and set accurately in adjusted position by other screw-threaded members or bolts 138. As shown, the clamping plates 134 are integral with a slide member 140 having a portion 142 which is dovetailed into a slot in a carrier 144, the slide member being secured in adjusted position by means of a set screw or other similar means 146 operative in a manner that is well understood. Extending upwardly from the carrier 144 is a circular boss 148 which is receivable in a closely fitting socket in the lower end of the plunger 150 shown as vertically reciprocable in the bearing 151 provided on the bracket 32. Extending through this boss and into a screw-threaded opening in the lower end of the plunger 150 is a bolt 152, or screw 152, by means of which the carrier is secured to the plunger, the arrangement being such that the carrier is freely rotatable on the plunger. Provision is preferably made for adjusting the carrier about the vertical axis of the plunger and holding it secured in adjusted position. With this object in view the carrier 144 is provided with outwardly extending wing members 154 (Fig. 7) which closely embrace flattened surfaces on opposite sides of a collar 156 surrounding and clamping firmly upon the lower end of the bearing 151. In adjusting the carrier 144 in the plunger it is necessary to loosen the bolts 158 of the collar 156, and turn the collar, thus causing the carrier to rotate on the screw 152 which passes through the carrier from below, whereupon the carrier may be again secured in adjusted position by properly manipulating the screw and 130

bolts aforesaid. Any other adjustment of the knife 132 may be secured by loosening set screw 146 and moving the slide 140 to the amount desired.

Preferably the plunger 150 (Fig. 5) is operated from a shaft 160 through an eccentric 162 and a pitman 164 connected to the plunger through a link 166 similar in all respects to the corresponding eccentric, pitman, and link of the operating connections described in connection with the die cutter shown in Fig. 4. Similarly the link 166 (Figs. 5 and 6) is pivoted at 168 to a lever 170 fixedly secured to a shaft 172 carried in a bearing 174 secured to the top of the bracket 32. In the position of the parts shown in Figs. 5 and 6, the pivot 176 which connects the pitman 164 with the link 166 is in the vertical longitudinal axis of the plunger 150 which passes through the center of the shaft 160 and hence rotation of the shaft 160 causes reciprocation of the plunger 150. If, however, the link 166 be moved to the left in Fig. 6 until the pivot 168 arrives at the position normally occupied by the pivot 176, then rotation of the shaft 160 causes an idle rocking movement of the link 166 about the pivot point 168 without affecting the plunger 150, the parts operating in the manner described in connection with the similar operating parts for the die plunger illustrated in Fig. 4. As above described, a bed plate 178 is provided for the link 166 and pivoted at 180 in the yoke 182 at the upper end of the plunger 150, said plate rocking slightly about the pivot 180 during oscillation of the link 166.

Means is preferably provided for automatically controlling the connections between the plunger 150 and its operating shaft 160, the said means comprising, in the construction shown, a controller member 184 (Figs. 5 and 6) pivoted at 186 to a bell crank 188 pivoted at 190 upon the bracket 32, the said controller member 184 being held with its lower end yieldingly in contact with the table 14 by means of a spring 185 attached at one end to the controller and at its other end to a pin 187 extending outwardly from the bracket 32. In order that the controller member may be confined to vertical movement, there is provided a link 192 pivoted at 194 to the controller and with its other end at 196 upon a bearing carried by the bracket 32. Preferably the lower end 195 of the controller member 184 is made detachable and is secured to the body of the controller by screws or bolts 198 and is so shaped that upon reversing said member 195 upon its vertical axis and in certain cases by also shifting it from one side of the body member 184 to the other side, the said end member 195 may be made to co-operate selectively with studs or cam blocks 200 positioned upon the table 14 in any one of four positions, for a purpose to be herein-after described. In the illustrative machine only three of the four positions will be utilized since only three cutters are employed. The cam blocks, as shown in Figs. 3, 5 and 6, have dovetailed portions so that they may be slidably engaged in slots in the upper surface of the table 14, spacing blocks 201 (Fig. 3) being also provided for use in properly positioning the said cam blocks 200, all of the blocks being retainable in proper position preferably by means of a readily operable catch or retaining member in the form of a spring, as shown at 203 (Fig. 3). Referring again to the bell crank 188, it will be observed that its upper end carries a pin 202 which is receivable in a slot 204 in a lever 206 (Figs. 1 and 5) pivoted at 208 to a lever arm 210 securely fixed to the shaft 172. As shown, the lever 206 carries intermediate of its ends a projection 212 provided with a roll 214 receivable in the fork 106 on the spider 108 which is reciprocable vertically as will be hereinafter more particularly described. It will be clear that vertical movement of the spider 108 (Fig. 1) will merely rock the lever 206 about its pivot point 208 when the stud 202 at the upper end of bell crank 188 is not in the forked end of the lever 206 and hence such vertical reciprocation of the spider will not rock the shaft 172. If, on the other hand, the controller member 184 be lifted against the spring 185 by means of one of the blocks 200 on the table 14 (Fig. 6), the pin or stud 202 on the bell crank 188 will be moved into the forked end of the lever 206 and become the fulcrum point for said lever. With the lever 206 fulcrumed as just described, vertical movement of the spider 108 will rock the lever 206 and thus, through the link 210, rotate the shaft 172 which controls the clutch or link connections between the shaft 160 and the plunger 150. Since the table 14 is intermittently rotated to present the cutting plates 16 successively to station A and to carry the work operated upon by the die at said station into position beneath the cutters, at other stations, for selective operation by the latter, it is clear that all of the cutters which should operate on the work presented must operate simultaneously while the table is at rest. Hence the spider 108 is in its lowermost position while the table is at rest, the spider having been moved to said position just at the termination of the preceding cycle, whereby the shaft 172 (Figs. 5 and 6) and the shaft 98 (Fig. 4) are so positioned that the links 92 and 166 respectively are held in the position shown in the said figures, so that rotation of the actuating shafts 80 and 160, respectively, will cause reciprocation of the plungers which actuate the cutters, both the die and the knife cutters. If, however, any one or

- more of the cutters 132 should not operate on the work at the time beneath them, there will be no cam block 200 opposite to said cutter to lift the controller member 184 and hence the fulcrum 202 for the lever 206 will not be in place and said lever lacking a fulcrum will not be operated to effect movement of the shaft 172. Thus there will be idle connections between the operating shaft 160 and the plunger carrying the cutter 132. It will be understood that the pin 202 must be disengaged from the forked end of the lever 206 while the spider 108 is in elevated position to leave the member 166 in the position shown in Fig. 6 of the drawings. Should there be any tendency of the member 166 to become displaced from its right-hand position in the said figure a spring will be used to retain it in the described position.
- At the beginning of the second half of the cycle of operations, the table 14 begins its rotation to carry the blocks 16 from one station to another and at this time the spider 108 is in elevated position and as the cam block 200 moves from under the controller member 184 the connection between the spider and the member 166 is rendered inoperative at the correct time to leave the member 166 in its left hand position in Fig. 6. Since in the last half of the cycle of operations the spider remains elevated until late in the cycle, it will be understood that the forked end of each lever 206 is maintained at its high point so that it can be entered by its corresponding pin 202 if the latter has been elevated by the controller 184 riding up on a cam block 200.
- Inasmuch as the material which is used in the production of pieced heel lifts is usually scrap leather, which often comes to the operator in a wrinkled, folded or corrugated condition, it is necessary to flatten or otherwise smooth out each piece before it is cut. For this purpose there is provided a presser member which flattens the piece of stock prior to the action of the die 20, the said presser member being associated with the die and arranged to be operated, in the preferred construction, through the die to hold the stock during the dieing-out operation. As shown, the presser member 220 is mounted as a plate slidably in the die 20 (Fig. 3) and backed by a spring 222 which surrounds a plunger 224 movable in the carrier 28 for the die, and up into a recess 225 (Fig. 4) in the lower end of plunger 76, so that the presser member 220 may yield into the die during the cutting of the blank. Means is preferably provided for engaging the blank cut by the die to hold it in its flattened or extended condition, otherwise the blank would again curl up or wrinkle or become otherwise displaced. For the purpose of holding the sheet material, there is provided, in the illustrative construction, a plurality of pointed members or pins 226 (Figs. 3 and 9) supported on a plate 228 and adapted to be projected through perforations 230 (Fig. 2) in each cutting plate 16, the construction and arrangement being such that the pointed members are projected to enter the blank cut by the die while the presser member is holding the material flat. It should be noted that the pointed members do not enter all parts of the material placed upon the cutting block but only the parts inside of the outline of the die where a whole lift is cut and, furthermore, the said pointed members enter only that portion of the material which is to constitute a lift section when the blank cut by the die shall have been trimmed by the cutters acting subsequently to the dieing-out operation. The reason for this arrangement of the pointed members or holding means lies in the fact that the waste parts must be swept from the table or otherwise removed before the lift sections arrive at the lift assembling station H. Because of the arrangement of the holding means or pointed members which, as shown, are so grouped as to outline the shape and approximate size of the blank or lift section to be cut on each individual cutting block, the perforations for the pointed members serve as an indicator and, broadly speaking, as a gage for the operator since he is enabled to tell at a glance the shape of blank which will be finally cut from material placed upon any given block and thus can select the pieces of scrap so as to utilize the material to the best advantage.
- The method of selecting and cutting the scrap material into lifts and into lift sections will be clear from a consideration of the disclosure in Fig. 2 of the drawings. Every piece of scrap is operated upon by the die at station A, the said die in its operation cutting a blank from the piece of material presented and conferring upon the blank whatever of permanent lift contour it will possess when assembled in a heel. If the piece of material is big enough to furnish a complete lift no other cutting operation is performed on said lift in its passage beneath all of the remaining cutters and hence these cutters must be so controlled as not to operate on the cutting block carrying said lift and hence opposite this cutting block (shown at station H) there is no stud or cam block 200 (see Figs. 2, 3, 5 and 6). With the cam block 200 absent, the controller member 184 is not operated to render the operating connections of the plunger for the cutter operative, as was made clear in the foregoing description. On the other hand, the cutting block shown in Fig. 2 at station A will be operated upon by two other cutters besides the die 20, the said cutters being indicated by the heavy dotted lines.

lines at stations B and C, the cutting plates which co-operate with the cutter shown at station B being shown at stations I, A and B, each cutting plate having opposite to it 5 a cam block 200 which operates the controller member 184 in the manner above described. For the sake of clearness, it is repeated that the blank shown on the cutting block 16 at station E was operated upon 10 at station A by the lift die 20 and at station B by the cutter shown in heavy dotted lines. The blanks shown on the cutting block 16 at stations F and G were both operated upon by the die at station A and by the knife 15 cutter at station D. The blank or lift section shown on the cutting block 16 at station D was operated upon by the die cutter at station A to produce the breast edge of the lift section and then was subsequently 20 operated upon by the cutters at stations B and C, and the blank or lift section at station C was operated upon by the die at station A and by the cutters at stations B and C. It will be observed that the various 25 cutters are controlled primarily by the cam blocks 200 which are positioned opposite to the cutting blocks 16 in such manner as to select the cutter or cutters which are to operate on the material on the given cutting block. Upon inspection of Fig. 2, it 30 will be obvious that the lift sections at F and G when assembled produce a complete lift. In the preferred construction, the lifts are assembled in the order at which they 35 arrive at the assembler at station H. Again the lift sections at stations E, D and C, when assembled, comprise a complete lift and the same is true of the sections at stations B, A and I, the cutting plate at station H supporting a complete lift. Hence 40 upon a partial rotation of the table 14 two pieced lifts may be assembled by one assembler, from the lift sections shown at stations G, F, B, A and I, to constitute a heel or heel 45 section and a complete rotation of the table will produce another heel or heel section collected by the other assembler from the whole lift at station H and lift sections from the cutting plates shown at the stations E, 50 D and C.

Operating at station H is the assembling means 22 comprising a plurality of assemblers, two in the illustrative machine, which co-operate alternately with the work supporting table to remove the heel lift sections or heel lifts from the table in such manner as to assemble the lift sections into lifts in superposed relation to each other, cementing means 24 being provided to co-operate 55 with each assembler to apply a layer of cement between adjacent surfaces of each pair of lifts. As above stated, a holder 26 for the assembled lifts which make a heel or heel section is provided into which the latter are forced under pressure, the holder 60 being of a sufficient length to permit of drying of the cement before the heels or heel sections are discharged at the lower end. The assemblers are also transmitters and carriers of lifts, receiving them at one station and depositing them at another station. In the illustrative machine each assembler comprises a head 236 (Fig. 9) comprising preferably part of a cross head or turret member 238 mounted at the upper end of a vertical shaft 240 so as to be rotatable and vertically reciprocable with the shaft. As shown, when one of the assemblers is positioned over the work supporting table at station H, the other assembler is directly over the upper open end of the holder 26. Removably attached to the lower end of the head 236 is a plate 242 which supports the head ends of a plurality of pointed members 244 against the lower surface of the head 236, the pointed members corresponding substantially in number to the perforations shown in the cutting plate at station B so as to be operative to pick each lift or lift section as the same is presented on successive cutting blocks. The plates 242 and the cutting blocks 16 are removable so as to be substituted by others of a different size or pattern, as may be desired. Mounted in the head 236 is a plunger 246 which passes through the plate 242 and has mounted on its lower end a stripper plate 248 which has perforations located to receive the pointed members 244. As the lifts and lift sections are collected on the pointed members 244, the plate 248 is forced upwardly until a heel or heel section of a predetermined thickness has been assembled. Pivoted at 250 on a lug extending laterally from the upper end of the plunger 246 is a trip lever 252 which extends downwardly through an opening in the cross head or turret to present a hook end 254 beneath a stationary hook abutment 256 on a plate 257 having also a cam 259 (Fig. 1). A pin 258 is provided in such position as to limit the movement of the trip lever under tension of the spring 260. Pivoted to the trip lever 252 intermediate of the ends thereof at 262 is a pawl 264 which extends transversely through a slot in the head 236 and through a corresponding slot in the plunger 246 and which is pressed upon constantly by a plunger 266 backed by a spring 268, both 105 in the upper portion of the plunger 246. The end of the pawl 264, when unlatched from over a plate 272 on the far side of the head opposite to the pivot for the said pawl, will rest on the top edge of said plate, 110 and during this time the hook end 254 of the trip lever is held out of engagement with the hook abutment 256 by reason of the contact of surface 270 on the trip lever with the pin 258. It will be observed, however, that as lifts or lift sections are assem-

bled, the plate 248 is moved upwardly carrying with it the plunger 246 and hence the trip lever 252 is also moved upwardly, whereby a surface 274 on the trip lever 252 is moved into position opposite the pin 258, the arrangement being such that the trip lever may move to the right (Fig. 9) when it is released by the pawl 264 to present the lower or hook end 254 in position to engage the hook abutment 256. For moving the trip lever to the left in Fig. 9 so that the pawl 264 may engage over the plate 272, there is provided on plate 257 the cam 259, above mentioned, which operates on the surface of the trip lever just above the hook 254 during the first part of the movement of the assembler away from the holder 26 and toward the cementing means 24. The release of the pawl 264 occurs when a shoulder 276 on the plunger 246 engages with the body of the pawl and lifts its end from operative engagement with the adjustable plate 272. The higher the plate 272 the thicker must be the heel section in the assembler to lift the plunger to unlatch the pawl. The unlatching occurs when a sufficient number of lifts have been assembled on the pointed lift retaining members 244. Then the trip lever is moved by spring 260 till surface 274 comes against pin 258 and upon the next reciprocation of the filled assembler in the position shown in cross sectional lines in Fig. 9, hook 254 engages beneath the abutment 256 and the plunger 246 is held from ascent with the cross head with the result that the heel section is stripped from the lift retaining members 244 and left in the holder 26. At a certain point in the upward movement of the cross head and assembler the pin 258 engages the surface 270 on the trip lever and causes the disengagement of the parts 254 and 256. For ensuring exact positioning of the cross head or turret upon each reciprocation there is provided a stud 278 projecting from the lower surface of the cross head and having a rounded end which is receivable in an opening 280 in the plate 257, which opening has a slightly flared upper end to receive and guide the stud and thus locate the cross head with respect to both the holder and the cutting block then at assembling station H. As shown, the lower end of the plunger 246 is reduced in cross-section where it passes through the plate 242 and for some distance above said plate, and in a socket surrounding the reduced portion within the head 236 there is provided a spring 284 surrounding the reduced portion and operative to lift the plunger 246 such a distance that the plate 248 at the lower end of the plunger is retracted slightly from the ends of the pointed members 244 where it will be in a plane slightly above the cementing roll of the cementing means 24

whereby cement is not applied to the plate 248, thus ensuring that no cement will be applied to the top surface of the first lift assembled by the assembler.

Between the holder 26 and the assembling station H on the cutting table there is positioned a cementing means shown in Figs. 1 and 11 as comprising a roll 290 mounted to turn with the shaft 292 in a cement reservoir 294 supported upon a bracket 296 from which it may be removed upon releasing the lock 298. One end of the shaft 292 carries a beveled gear 300 which is constantly in mesh with a co-operating beveled gear 302 on the shaft 240. Preferably the bracket 296 is supported by a spring 304 having its lower end resting on a stationary bracket 306 and receivable in a socket 308 in the first mentioned bracket. The spring is of such a tension as to hold the beveled gears 300, 302 in engagement with each other and yet permit a slight downward movement of the bracket 296 with its cementing roll to accommodate heel sections which may vary slightly in their vertical dimensions, it being understood that the assembler picks up a complete lift or a pieced lift from the work supporting table at station H and carries the said lift over the roll to apply paste to the lower surface thereof, this operation occurring as the assembler moves from the holder 26 back to station H. It is to be understood that the cross head 238 which carries the assemblers makes a half rotation, each time a complete lift is assembled at station H, to interchange the assemblers, the one from station H going to a position over the holder 26, and that it is upon the return from the holder to station H that the cement is applied, the cross head making a complete rotation in one direction in two steps, thus making it possible for one assembler to collect lifts or lift sections at station H while the other assembler is over the holder 26 in which the assembled lifts may be deposited when sufficient have been accumulated to make a heel or heel section of the desired number of lifts. By thus positioning the cementing roll so that cement is applied upon the return of the assembler from the holder toward station H, it is clear that no cement is applied to the bottom surface of the last lift assembled at station H. Since, as pointed out above, no cement is applied to the top surface of the first lift and none to the bottom surface of the last lift, the heels or heel sections deposited in the holder 26 will not adhere to each other so that distinct and entirely separate heels or heel sections are piled up in the holder.

When the cutting blocks arrive at station H where the lifts are assembled by the assembling means, the latter operates upon reciprocation of the shaft 240 to cause the pointed members or lift retaining means

244 of the assembler to penetrate the lift or lift section on the given cutting plate at that time positioned at station H. After the members 244 have penetrated the lift or lift section the lift holding members or pins 226 are withdrawn downwardly, this timing of the operations being for the purpose of ensuring that the blanks or lift sections are retained in their flattened or extended 10 condition, it being clear that if the pins 226 were withdrawn before the retaining members 244 entered the blanks, the latter might curl up or wrinkle for reasons set forth in the foregoing description. Preferably the 15 lower surface of the plate 312 is provided with a hook 314 (Fig. 9) which comes into engagement with a corresponding hook member 316 at the upper end of a rod 318 which is vertically reciprocable in bearings 320 in the frame of the machine. In the 20 illustrative construction the lower end of the rod 318 has a reduced portion 322 which passes slidably through the end 324 of an arm 326 carried by sleeve 328 in turn 25 slidably on a reduced portion 330 of the vertical shaft or rod 240. Mounted on the lower end of the plunger 240, which is further reduced, is a spring 332 having one end in 30 engagement with a washer 334 in abutting relation with the lower end of the sleeve 328, the other end of the spring 332 being in contacting relation with lock nuts 336 on the lower end of the shaft 240. Mounted 35 on the sleeve 328 is a stud 338 carrying a roll 340 movable in a cam slot 342 in the cam wheel 344 secured to the main shaft 346. Upon rotation of the shaft 346 the vertical shaft 240 is reciprocated and is pulled down yieldingly because of the interposition of the spring 332 between the sleeve 328 and the nuts 336 at the lower end of 40 said shaft. It will be clear that the assembler 236 mounted on the shaft 240 is moved downwardly to cause the pointed lift retaining members 244 to engage the lift on the block at station H and that subsequently the pins 226 are pulled downwardly through engagement of the arm 326 on the sleeve 328 with the lower end of the 45 rod 318, a lost motion connection being provided between said arm and the rod which causes the withdrawal of the pins 226 only after an interval as described. At station H there is a depression in the support for the table 14 which permits this downward movement of the plate 312 which carries the pins 226. Similarly at station A (Fig. 8), the plates 312 and 228 which are secured together are pulled downwardly to withdraw the pins 226 to permit of the piece of work being positioned flat upon the cutting block through the operation of the presser member 220 in the die 20, the said downward movement of the plates being caused by a hook member 316 at the upper end of 50 the rod 350 which is similar as to its hook construction to the rod 318. For operating the hook member or rod 350 there is provided a spring 352 engaging a surface 354 on the frame of the machine and a collar 55 70 356 on the rod 350. While each cutting plate 16 is approaching the station A, the rod 350 is held in its upper position so that the hook thereof may engage over the hook 314 on the plate 312. As soon, however, as 75 the given cutting block has arrived at station A, the cam roll 360 on one end of the lever 362 drops into one of two diametrically-opposed cam grooves 364 in the cam 366 on the lower surface of the wheel 368, thus permitting the spring 352 to actuate the rod 350 downwardly, withdrawing the pins 226 to inoperative position. The cam 366 is so constructed and arranged, 80 85 however, as to project the pins upwardly through the operation of the rod 350 before the presser member 220 is withdrawn and the said plates 312, 228 are held upwardly by the surface of the support for the table until station H is reached where, 90 as above described, it is again necessary to provide means to move the said plates downwardly and retract the holding pins. 95

The holder for the heels or heel sections which are received from the assemblers consists preferably of four angle bars, as shown in Figs. 1, 9, 10 and 12, having flared upper ends so that the heels or heel sections may be readily forced into the holder which is constructed yieldingly to engage the edges 100 of the articles. Referring to Figs. 9 and 12, it will be observed that the upper ends of the angle bars 380 are provided with lugs 382 extending laterally therefrom and which are arranged to be secured to adjustable members 384 by means of screws or other retaining members 386, the adjustable members being carried by a bracket 388 extending from the frame of the machine and adjusted toward and from each other by a screw 389 held against endwise movement by a pin as shown in Fig. 12. Mounted in extensions 390 (Fig. 9) on said bracket are screw threaded members 392 and slidable on 105 said members is a cross bar 394 having sockets therein surrounding the bars and in the sockets springs 396 (Fig. 1) are operable to yieldingly press the cross bar 394 in the direction of the bracket extensions 390. Both rods 392 have knurled heads rendering it easy to rotate them for adjustment purposes when it is desired to adjust the holder to articles of various sizes. The cross bar 394 is provided with upstanding lugs 398 in pairs in which are pivoted ears 400 integral with or securely attached to the upper ends of the angle bars 402 which constitute the remaining sides of the holder. 110 As will be observed from an inspection of Figs. 9 and 10, the lower ends of the angle 115 120 125 130 bars 402 are provided with ears 404 which are secured to the frame of the machine.

bars 380 and 402 are provided with grooved members 404 around which pass one or a plurality of springs 406 encircling the holder and operating yieldingly to retain

the angle bars against outward expansion as the heels or heel sections are forced down through the holder. The holder is therefore a press into which the heels or heel sections are forced under pressure and held until dry enough to be removed.

Means is preferably provided for sweeping the waste portions of the material from the table, waste portions being indicated on the cutting blocks in Fig. 2 at stations C, D, E and F. For this purpose there is provided (at station G) in the illustrative construction a brush 412 (Fig. 8) secured to the lower end of a lever 414 pivoted at 416 and carrying a cam roll 418 at its upper end for movement along the cam groove 420 in the cam wheel 422. As shown, the cam wheel is carried by the shaft 424 mounted in the frame of the machine and having a beveled gear 426 in constant mesh with the large beveled gear 428 secured to rotate with the shaft 430. As the brush 412 is moved inwardly it sweeps the material from the table 14 into the upper end of a chute 432, the mouth of the chute being guarded by a U-shaped scrap receiving member 434 open toward the cutting blocks and supported by a bracket 436 secured to the standard 34 of the machine. When the brush swings in the opposite direction the piece or pieces of scrap located on the other side of the lift section held by the retaining pins is brushed over the edge of the table into a receptacle positioned at the outlet of the chute 432. Preferably the openings 438 in the table 14 opposite each cutting block 16 are closed at their lower ends by a plate 440 secured to the support on which the table rests, as shown in Fig. 3, the said plate extending beneath the openings 438 and making a complete circle except for the upper end of the chute 432, whereby waste material is discharged at one point only and provision is made for preventing waste pieces or other material from falling into the gearing placed below the table.

While in Fig. 2, nine cutting blocks are utilized, it may be advantageous to make use of other numbers, for example, seven under certain conditions, the ones shown at stations F and G and the corresponding cam blocks 200 and controllers 500 being omitted. If the stock being cut by the die 20 is relatively heavy, brackets 441 (Figs. 1 and 3) may be bolted in place at stations E and F to back up the standard 34 against the thrust of the die operating at station A. It will be understood, of course, that brackets similar to those shown in Fig. 1 may be constructed to brace the standard 34 without interfering with the attachment of

additional cutting devices if such should be desired, and that such strengthening brackets may be supplied by any skilled mechanic.

In the illustrative construction power means for driving the machine comprises an electric motor 450, the armature shaft of which carries a pulley 452 which is belted to a large pulley 454 on a shaft 456 below and parallel with the armature shaft. This last mentioned shaft 456 has fixed thereto a beveled gear which is constantly in mesh with a large gear 458 which turns loosely on the main shaft 346. Interposed between the gear 458 and the shaft 346 is a clutch and brake mechanism 460 which may be of any improved type, not herein disclosed but shown in applicant's copending application Serial No. 414,410, filed August 18, 1920, or of any old and well-known construction designed to effect a single revolution of the shaft 346 upon each actuation of the starting means by the operator. As above described, the starting means comprises a handle 56 (Fig. 1) and connections leading through the shaft 68 and link 72 (Figs. 1 and 3) to a lever arm 462 on a rock shaft 464 which carries another arm 466 that directly operates the clutch 460. As before stated, a single actuation of the hand lever 56 causes a single revolution of the main shaft 346. Securely fixed to the shaft 346 is a beveled gear 468 (Figs. 3 and 9) which is disposed constantly in mesh with a beveled gear 470 fixed on the lower end of the upright shaft 430 mounted in bearings in the frame of the machine, one of which is shown at 472. Secured to the shaft 430 is the cam wheel 368 provided with two diametrically opposite studs carrying rolls 474 (Fig. 2) designed to enter the cam grooves 476 in a wheel 478 secured to the lower end of the shaft 480 (Fig. 9). As shown the wheel 478 carries four studs having rolls 482 thereon which are arranged to enter between upstanding flanges 484, 486 on the large cam wheel 368, the construction and arrangement being such that the rolls 474 on the cam wheel 368 enter the cam grooves 476 in the smaller wheel 478 to rotate the latter while the rolls 482 on the wheel 478 co-operate with the flanges 484, 486 to lock the wheel 478 against rotation in the intervals when neither of the rolls 474 are engaged with the wheel 478, the whole arrangement constituting an equivalent of other and better known forms of the Geneva movement mechanism. Securely fixed to the shaft 480 is a small gear 488 arranged in mesh with a larger gear 490 which is securely attached to the lower surfaces of the table 14. Hence upon rotation of the shaft 480 intermittently as provided for by the Geneva movement, the table 14 makes one-ninth of a revolution to each complete revolution of the main shaft 346.

The reason for this arrangement will be made clear upon reference to Fig. 2 of the drawings wherein it is seen that the table 14 carries nine cutting blocks 16, each one of which stops at station A beneath the cutting die 26, the arrangement being such that the table stops in position with a cutting block at station A upon which the operator may position the work. Attached to the upper end of the shaft 430 is a cam wheel 492 having a cam groove with two rises and two low parts along which travel rolls 494 secured on studs fixed on the spider 108. The upper end of the shaft 430 also carries fixedly attached thereto a beveled gear 428 for driving a plurality of small beveled gears 498 on the shafts 80 and 160 for operating the die and cutter plungers. The gear 428 bears a relation to gear 498 of four to one in order that the shafts for operating the die and cutter plungers shall operate at high speed and thus render effective the operative blow of the plungers. The spider 108 is moved up and down once during each cycle of the machine so as to control the link clutch mechanisms interposed between each shaft 80 and 160 and the corresponding die and cutter plungers so that the latter will not be operated during the second revolution of the gears 498 in the same cycle of the machine. As shown, the spider is prevented from turning by reason of the engagement of an arm 499 (Fig. 8) in a vertical slideway 501 in a bracket fixed to an arm of the machine frame. It will be understood that when the table 14 comes to rest at the end of a cycle the spider 108 is at its lowermost position and all of the controllers 184 of the cutting devices which are to operate in the succeeding cycle have been operated by the cam blocks 200 so as to render the link clutches of the cutter plungers operative as above described. Then when the operator starts the machine by the handle lever 56 the selected shafts 160 and the shaft 80 operate to effect a dieing-out and a plurality of cutting operations.

At the same time the cutters are operating on the work on the table the assembler is also operated to collect and assemble the lift section at station H, the assembler being actuated in properly timed relation by means of the cam wheel 344 on the main shaft 346 as above described. While the assembler is reciprocated at each cycle of the machine it is rotated at irregular intervals since it must reciprocate toward and from the work supporting table a varying number of times to collect an entire lift. Referring to Fig. 2, it will be clear that the assembler must reciprocate twice to collect the lift sections from the cutting blocks 16 shown at stations F and G in order to assemble one complete lift. Again the assembler must reciprocate 65 toward and from the table 14 three times to

collect one complete lift from the cutting blocks shown at stations C, D and E and only once to collect a complete lift from the cutting block shown at station H. For this reason the table 14 carries controller members 500 which operate to determine the time of operation of the rotating means for the assemblers. The reason that the assembler does not rotate for each cycle of the machine is due to the fact that it is of course desirable to collect one entire lift before rotating the assembler over the cementing means and hence the controller members above described are so positioned with respect to cutting blocks 16 as to cause the actuation of the rotating means after a complete lift has been assembled in the assembler. For example, the controller 500 at station F causes an operation of the rotating means for the assembler after the lift sections at stations G and F have been collected in the order named. When the table 14 comes to rest at the end of a cycle of operations one of the controller members 500, shown at stations I, C, F and H, may be in position to cause operation of the assembler rotating means. When it is in such position, it will occupy the dotted line position shown at station H in Fig. 9, in which case it will depress the vertically movable rod 502 which is slidable in a bracket extending from the machine frame and which is arranged to contact with the bolt 504 normally in raised position through the operation of the spring 506 to drive the bolt downwardly into an opening 508 in a plate 510 secured to a gear 512, thus locking the wheel 514 to the gear 512, the latter being driven by means to be described. Since the wheel 514 is keyed to the shaft 240, means is provided through the bolt and plate connections just described for clutching the gear 512 to the shaft to cause rotation of the latter and thus of the assemblers. Preferably a second bolt 516 is provided similar to the bolt 504 and arranged to be driven into a similar opening 508 in the plate 510 by means a cam surface 518 which engages the head of the bolt 516 upon rotation of the wheel 514, thus the more securely locking the wheel to the gear 512. It will be understood that this locking or clutching of the gear 512 to the wheel 514 by means of the bolt 504 occurs when a controller 500 on the table 14 comes in contact with the upper end of the slide member 502 at the termination of a cycle of operations of the machine and just as the table comes to rest. When the machine is started again, the assembler will first be reciprocated through the action of the cam 344 on the main shaft 346 as above described practically at the same time that the cutters and die operate upon other pieces of the work, and then later in the same cycle the table 14 turns and at the same time the assembler turns because 130

of the operation of the gear 512 which is driven from a gear wheel 520 on the shaft 480, through which shaft the table 14 is driven as above described, and an intermediate gear 522 interposed between the gear 520 and the gear 512 (Fig. 2). It will be understood that the assembler at station H picks up a lift or lift section from the table 14 at the same time that a built up heel section of two or more lifts is forced into the holder 26 by the other assembler. If, however, the assembler over the holder carries only one lift it will not be deposited in the holder since the trip lever 252 is not in position to be engaged by the abutment hook 256 for reasons above described. Hence, on the next rotation of the assemblers, the lift carried by the assembler shown over the holder in Fig. 9 will move the lift over the cementing roll (Fig. 1) and return to position over the table at station H where another lift will be assembled through the predetermined number of reciprocations of the assembler, cement being applied between each two lifts in the manner described.

In the operation of the machine the pieces of material are placed upon the cutting block 16 which at the time is at station A, the operator being guided in the selection of the piece of material by the perforations in the cutting block which outline the size and shape of the blank which will be cut in the co-operation of cutters and cutting block. When the material has been positioned, the operator operates the handle 56 (Fig. 1), in the manner described, by which the die is caused to operate on the material and by which the machine is started to cause the operation of the other cutters in the manner described. Since the machine is automatic in its operations after the positioning of the work, the operator has practically only one die to attend to and in the cycles of operations heel sections or heels of predetermined heights are built up and deposited in the holder.

Having thus described my invention, what I claim as new and desire to secure by Letters Patent of the United States is:

1. In a machine of the character described, a work support, means for cutting sheet material positioned on the support into complementary blanks of different shapes, and means co-operating with the support for automatically assembling the blanks in predetermined relation to make a complete article.

2. In a machine of the character described, a work support and means co-operating therewith for cutting complementary blanks of different shapes from sheet material and for automatically assembling the blanks in predetermined relation in the same plane to produce a complete article.

3. In a machine of the character described, means for cutting from sheet material blanks of different shapes in predetermined order, and means for automatically assembling the various blanks to make a complete article.

4. In a machine of the character described, means for cutting from sheet material blanks of different shapes automatically in predetermined order, and means for assembling certain of the blanks to make a complete article and other blanks of different shapes from those last mentioned to produce another article of the same shape as the first.

5. In a machine of the character described, a work support, and means co-operating therewith for cutting complementary lift sections from pieces of sheet material and for assembling said sections into lifts.

6. In a machine of the character described, means for cutting from sheet material blanks of different shapes automatically in predetermined order, and means for assembling certain of the blanks to make an article and other blanks of different shapes from those first mentioned to provide an article of the same shape as the first and for assembling the articles in superposed relation.

7. In a machine of the character described, means for cutting pieces of leather into lift sections of various shapes, and means for automatically assembling certain of the lift sections to make a complete lift and for assembling other lift sections of different shapes from the first to produce a complete lift of the same size and shape as the first and constructed and arranged for assembling lifts in superposed relation.

8. In a machine of the character described, means for cutting pieces of leather into lift sections of various shapes, means for automatically assembling certain of the lift sections to make a complete lift and for assembling other lift sections of different shapes from the first to produce a complete lift of the same shape as the first, and means for securing the lifts together in superposed relation.

9. In a machine of the character described, means for cutting pieces of leather into lift sections of various shapes, means for automatically assembling certain of the lift sections to make a complete lift and for assembling other lift sections of different shapes from the first to produce a complete lift of the same size and shape as the first, and means for applying a layer of cement between the lifts to secure them together in superposed relation.

10. In a machine of the character described, means for cutting pieces of leather into lift sections of various shapes, means for automatically assembling certain of the lift sections to make a complete lift and for assembling other lift sections of different

- shapes from the first to produce a complete lift of the same size and shape as the first, and means for assembling the lifts in superposed relation and for interposing a layer 65 of cement to secure them together.
11. In a machine of the character described, a work support, means for cutting pieces of leather positioned on the support into lift sections of various shapes, and 70 means for assembling the lift sections into complete lifts in superposed relation.
12. In a machine of the character described, a die for operating on pieces of leather to produce the permanent peripheral 75 contour lines of lift sections, a plurality of cutters automatically operative to make cuts which intersect the said contour lines of the lift sections, and means for automatically assembling the lift sections into complete lifts.
13. In a machine of the character described, a table having a cutting surface, a plurality of cutters above the surface, and means for operating the table and the cutters in such timed relation as to produce lift 80 sections of various shapes in a predetermined order so that as the lift sections are assembled in said order complete lifts are formed.
14. In a machine of the character described, a table having a work-supporting 85 surface, a plurality of cutters mounted above the table for co-operation therewith, and means for operating the cutters in a predetermined order to produce lift sections of various shapes collectable at a given station 90 in the order in which they arrive to produce complete lifts from the variously shaped lift sections.
15. In a machine of the character described, a table having a cutting surface, a plurality of cutters for cutting lift sections from pieces of leather supported on the table, means for operating the cutters in a predetermined order, means for varying the order, and means for collecting the sections 95 as they arrive at a given station to produce complete lifts in superposed relation.
16. In a machine of the character described, a table having a cutting surface, a die and a plurality of cutters mounted above the table opposite to the cutting surface, means under control of the operator for operating the die to produce a permanent lift contour cut on sections of lifts, means 100 for operating the cutters to cut the lift sections along lines which intersect the permanent lift contour cut, and means for assembling the lift sections into complete lifts.
17. In a machine of the character described, a table having a plurality of cutting surfaces thereon, means for holding pieces of sheet material properly disposed on said surfaces, a heel lift die for making a permanent heel lift contour cut on the lift sections, 105 and a plurality of cutters controlled by the table for making cuts in the pieces of material which intersect the lift contour cut produced by the die.
18. In a machine of the character described, a table having a plurality of cutting surfaces thereon, means for holding pieces of sheet material properly disposed on said surfaces, a heel lift die for making a permanent heel lift contour cut on the lift sections, a plurality of cutters controlled by the table 110 for making cuts in the pieces of material which intersect the lift contour cut produced by the die, and means for assembling the lift sections into lifts with the edges produced by the latter cuts closely abutting each other.
19. In a machine of the character described, a table having a plurality of cutting surfaces in spaced relation thereon, a heel lift die, arranged for co-operation with all the cutting surfaces in succession, for cutting pieces of sheet material to produce lift contour cuts on the pieces, a plurality of cutters for co-operation selectively with the cutting surfaces on the table for cutting the pieces along lines which intersect the contour cuts 115 of the pieces, means for rotating the table intermittently to position the pieces of work successively under the various cutters, and means controlled by the table for operating the cutters in predetermined order to make the intersecting cuts and thus produce lift sections which are collectable in the order in which they arrive at a given station to produce complete lifts.
20. In a machine of the character described, a table having a plurality of cutting surfaces in spaced relation thereon, a heel lift die for cutting pieces of sheet material to produce lift contour cuts on the pieces, a plurality of cutters for co-operation selectively with the cutting surfaces on the table 120 for cutting the pieces along lines which intersect the lift contour cuts of the pieces, means for rotating the table intermittently to position the pieces of work successively under the various cutters, means controlled by the table for operating the cutters in predetermined order to make the intersecting cuts on the lift sections and thus produce sections which are collectable in the order in which they arrive at a given station to produce complete lifts, and means at said station for collecting the lift sections in superposed relation to make a heel or heel section.
21. In a machine of the character described, a work support, a die mounted for movement about a horizontal axis from and into position to co-operate with the work support and normally displaced so as to uncover the work support while work is being positioned thereon, power means for operating the die, and a manually operable lever 125

for moving the die to operative position over the work support and for causing power operation of the die.

22. In a machine of the character described, a work support, a die for co-operation with the work support in cutting blanks from sheet material, a presser member associated with the die for flattening out the work prior to the cutting operation, and means associated with the support for holding the died blank in properly disposed relation on the support.

23. In a machine of the character described, a work support, a die for co-operation with the work support in cutting blanks from sheet material, a presser member associated with the die for flattening out the work prior to the cutting operation, and means operable through the support to act on the blank to hold it in properly disposed relation on the support.

24. In a machine of the character described, a work support, a die for co-operation with the work support in cutting blanks from sheet material, a presser member associated with the die for flattening out the work prior to the cutting operation, and pointed members movable through the support to penetrate the blank and hold it in properly disposed relation on the support.

25. In a machine of the character described, a work support, a die for co-operation with the work support in cutting blanks from sheet material, a presser member movable through the die for flattening out the work prior to the cutting operation, and pointed members movable through the support while the presser member holds the blank thereon to penetrate the blank to hold it in properly disposed relation on the support.

26. In a machine of the character described, a work support for sheet material, a cutter movable toward and from the support to cut blanks from the sheet material, a shaft having an eccentric thereon, a pitman operated directly by the eccentric, a plunger arranged to be operated from the eccentric through said pitman to force the cutter through the sheet material, and a clutch between the eccentric and the plunger for controlling the operation of the cutter.

27. In a machine of the character described, a work support for supporting sheet material, a die movable toward and from the support to cut the sheet material into blanks, power means for moving the die during cutting operations comprising a shaft having an eccentric thereon, a plunger for directly operating the die, an eccentric strap and pitman operatively connecting the eccentric with the plunger, and a link movable to position the pitman in alignment with or out of alignment with the plunger and thus control the operation of the die.

28. In a machine of the class described, a movable table having a plurality of work supporting surfaces, a die for cutting blanks from sheet material positioned on said surfaces, and cutters for selectively operating on the blanks cut by the die as the table is moved to position said blanks successively in co-operative relation with the cutters.

29. In a machine of the class described, a table having a plurality of work supporting surfaces, a die for successively cutting blanks from sheet material supported on each of said surfaces, and a plurality of devices arranged to co-operate selectively with said work supporting surfaces and to be controlled by the table for treating the blanks after they have been operated upon by the die.

30. In a machine of the class described, a rotatable table having a plurality of work supporting surfaces, a die for successively cutting blanks from sheet material supported on said surfaces, a plurality of cutters for operating on the blanks, and means carried by the table for controlling the operation of said cutters.

31. In a machine of the character described, a rotatable table having a plurality of work supporting surfaces, a die under the control of the operator for successively dieing out blanks from sheet material supported on said surfaces, means for holding each blank in the exact position in which it was operated upon by the die, a plurality of cutters mounted in co-operative relation with the table, and means for automatically operating the cutters to cut the blanks, made by the die, along different predetermined lines.

32. In a machine of the character described, a rotatable table having a plurality of work supporting surfaces, a die for successively operating on sheet material supported on said surfaces to cut blanks therefrom, cutters mounted in co-operative relation to said surfaces on the table for operating on the blanks as they are successively presented to the cutters, and means for assembling the blanks in predetermined relation to form a complete article.

33. In a machine of the character described, a table having a plurality of work supporting surfaces, a die for successively operating on sheet material supported on the surfaces to cut blanks therefrom, a plurality of cutters mounted above the table in co-operative relation with said surfaces, means for turning the table to present the blanks cut by the die successively in position beneath the cutters, means for operating the cutters to provide straight edges on the blanks, and means for assembling the blanks in side-by-side and in superposed relationship to form complete articles.

34. In a machine of the character de-

- scribed, a table having a work supporting surface, cutters for operating on sheet material on said surface for cutting blanks therefrom of various predetermined shapes, 5 and means for assembling said blanks to form articles.
35. In a machine of the character described, a movable work support having a plurality of work supporting surfaces, cutters arranged for co-operation with the movable work support to cut blanks of various predetermined shapes from sheet material supported on said surfaces, and means for assembling said blanks to form articles.
- 15 36. In a machine of the character described, a work support having a work supporting surface, cutters arranged for co-operation with the work support to cut blanks of various predetermined shapes 20 from sheet material supported on said surface, and means for assembling said blanks in side by side and in superposed relationship to form articles.
- 25 37. In a machine of the character described, a rotatable table having a plurality of work supporting surfaces, a die for cutting blanks from sheet material supported on the surfaces, cutters mounted in co-operative relation with the table for operating 30 on the blanks cut by the die, certain of said cutters being arranged to cut blanks along lines angularly related to each other, means for operating the cutters in a predetermined order to produce blanks of different 35 shapes, and means for assembling the said blanks to produce articles.
38. In a machine of the character described, a rotatable table having a plurality of work supporting surfaces, a die for successively cutting blanks from sheet material supported on said surfaces, a plurality of cutters arranged for co-operation with said surfaces, means for operating the cutters to cut certain of the blanks formed by the die along lines angularly related to each other and others of the blanks to provide a straight edge thereon, controlling means carried by the table for determining the operation of the cutters whereby blanks of 45 different shapes are produced, and an assembling means for taking the blanks from the table and assembling them in side by side and in superposed relationship to form complete articles.
- 50 39. In a machine of the character described, a rotatable work supporting table having a plurality of work supporting surfaces, a die for cutting blanks from sheet material supported on the surfaces, a presser member associated with the die for flattening out the sheet material before it is cut, holding members mounted in the table for penetrating each blank from beneath to hold it in flattened or extended position on the work supporting surface, cutters for operating on the blanks while they are held by the holding members, and an assembler for picking up the blanks during the rotation of the table in such manner that they occupy a predetermined relation to each other and form complete articles.
- 55 40. In a machine of the character described, a movable work supporting table having a plurality of work supporting surfaces, a die for cutting blanks from sheet material supported on the table, a presser member in the die for flattening out the sheet material before it is cut, holding members mounted in the table for penetrating each blank from beneath to hold it in flattened or extended position on its work supporting surface, cutters for operating on the blanks held by the holding members, an assembler comprising a plurality of penetrating members arranged to enter each blank before the blank holding members are withdrawn, and means for operating the assembler intermittently in timed relation with the movements of the table to pick up blanks successively from the table and hold them in assembled relation.
- 60 41. In a machine of the character described, a movable work supporting table, a presser member for flattening out the sheet material before it is cut, holding members mounted in the table for penetrating the material from beneath to hold it in flattened or extended position on the table, cutters for operating on the material to cut blanks therefrom, an assembler comprising a plurality of penetrating members arranged to enter each blank before the blank holding members are withdrawn, means for operating the assembler intermittently in timed relation with the movements of the table to pick up blanks successively from the table and hold them in assembled relation, a cementing means, and means for operating the assembler to apply cement between the layers of blanks whereby the layers are held together to make a complete article.
- 65 42. In a machine of the character described, a table having a plurality of work supporting surfaces, a plurality of cutters for operating on sheet material supported on said surfaces to produce blanks of various predetermined shapes, means for moving the table intermittently to position blanks for the operation of said cutters, and an assembler for picking up the blanks successively from the table and assembling them in the form of complete articles.
- 70 43. In a machine of the character described, a table having a plurality of work supporting surfaces, a plurality of cutters for operating on sheet material supported on said surfaces to produce blanks of various predetermined shapes, means for moving the table intermittently to position blanks for the operation of said cutters, and an assembler for picking up the blanks successively from the table and assembling them in the form of complete articles.

bler for picking up the blanks and maintaining them in the same relative position which they occupy on the table whereby the blanks are assembled in proper side by side 5 relationship to form complete articles.

44. In a machine of the character described, a table having a work supporting surface, a plurality of cutters for operating on sheet material supported on said surface 10 to produce blanks of various predetermined shapes, means for moving the table intermittently to position blanks for the operation of said cutters, an assembler for picking the blanks from the table and holding them 15 in predetermined relation to each other, a cementing member, means for operating the assembler with relation to the cementing member to apply a layer of cement between the opposed surfaces of the blanks, and 20 means for operating the assembler to cause it to eject the complete article formed of a predetermined number of layers of blanks.

45. In a machine of the character described, a table having a work supporting 25 surface, a plurality of cutters for operating on sheet material supported on said surface to produce blanks of various predetermined shapes, means for moving the table intermittently to move successive blanks in position 30 for the operation of said cutters, an assembler for picking the blanks from the table and holding them in predetermined relation to each other, a cementing member, means for operating the assembler with relation to 35 the cementing member to apply a layer of cement between the opposed surfaces of the blanks, a holder for articles, and means for operating the assembler to build up articles of a predetermined thickness and for causing 40 the assembler to eject the articles successively into said holder.

46. In a machine of the character described, a table having a work supporting surface, a plurality of cutters for cutting 45 heel lift sections of different shapes from pieces of leather supported on said surface, an assembler for picking up lift sections of complementary shapes to form complete lifts, cementing means, a holder for heel sections, 50 and means for operating the assembler to apply cement between adjacent surfaces of the assembled lifts and for depositing the heel sections thus formed in said holder.

47. In a machine of the character described, a table having a work supporting surface, a plurality of cutters for cutting heel lift sections of different shapes from pieces of leather supported on said surface, an assembler for picking up lift sections of 60 complementary shapes to form complete lifts, a holder for heels or heel sections, a cementing means located between the holder and the assembling position of the assembler, and means for operating the assembler to pick up 65 lift sections from the table in such manner

as to form complete lifts in superposed relation to each other and for moving the assembler so that cement is applied to the opposed surfaces only of the lifts and for causing the assembler to force the assembled lifts 70 or heel sections into said heel holder.

48. In a machine of the character described, a table having a work supporting surface, cutters for cutting heel lift sections of various shapes from pieces of leather supported on said surface, an assembler for picking up complementary lift sections from the table to form complete lifts in superposed layers, cementing means for applying cement between adjacent surfaces of the 75 pieced lifts thus forming heels or heel sections, and means controlled by the thickness of the heel section thus assembled in the assembler for causing the assembler to eject the heel section. 80

49. In a machine of the character described, a table having a work supporting surface, cutters for cutting heel lift sections of various shapes from pieces of leather supported on said surface, an assembler for picking up complementary lift sections from the table to form complete lifts in superposed layers, cementing means for applying cement between adjacent surfaces of the pieced lifts 85 thus forming heels or heel sections, and means controlled by the thickness of the heel section thus assembled in the assembler for causing the assembler to eject the heel section, said last named means being adjustable so that heel sections of various predetermined thickness may be formed and automatically ejected from the assembler. 90

50. In a machine of the character described, a table having a work supporting surface, cutters for cutting heel lift sections 100 of various shapes from pieces of leather supported on said surface, cementing means for applying cement between adjacent surfaces of the pieced lifts thus forming heels or heel sections, a holder for heel sections of such a 105 length as to permit drying of the heels during their passage therethrough, an assembler for picking up complementary heel lift sections from the table to form complete lifts in superposed relation, and means for operating the assembler to apply cement between the 110 opposed surfaces of the lifts and for ejecting the heel sections thus formed into said holder. 115

51. In a machine of the character described, a table having a work supporting surface, cutters for operating on pieces of leather to form lift sections of various shapes, assembling means comprising a plurality of assemblers each designed to pick 120 up lift sections from the table in such manner that complementary lift sections are arranged in closely abutting relation to form complete lifts in superposed relation, a holder for assembled heel sections, and means 125 130

for operating the assemblers in such manner that as one assembler is assembling lifts another assembler is depositing a complete heel section in said holder.

52. In a machine of the character described, a table having a work supporting surface, cutters for operating on pieces of leather to form lift sections of various shapes, assembling means comprising a plurality

- 10 of assemblers each designed to pick up lift sections from the table in such manner that complementary lift sections are arranged in closely abutting relation to form complete lifts and in superposed relation to
- 15 form heels or heel sections, a holder for assembled heel sections, a cementing means located between the holder and the station where the lift sections are assembled, and means for operating the assemblers to apply
- 20 cement to the opposed surfaces only of the complete lifts and for causing one of the assemblers to deposit the completed heel section in said holder at the same time that another assembler is assembling lift sections
- 25 from said table.

53. In a machine of the character described, a table provided with a plurality of cutting blocks upon which the work is supported during cutting operations, each block being provided with perforations grouped in such a way as to outline the shape of the blank which will be formed from the material positioned on that block, a plurality of members arranged to pass through the

- 30 perforations and having sharpened ends designed to penetrate the material positioned on the block to hold the material in proper position, and cutters for operating on the material on the cutting blocks to cut blanks
- 35 therefrom of the shapes defined by the groups of perforations.

54. In a machine of the character described, a table provided with a plurality of cutting blocks, each cutting block having a

- 40 plurality of perforations passing therethrough and grouped in such a way as to outline the shape of the blank which will be cut from the material positioned on that block, a plurality of pointed members mounted to pass through the perforations in each block, a presser member operative to flatten the material on each block prior to cutting operations, means for operating the pointed members to cause them to penetrate the material on the block while the presser member holds the material flat, the pointed members being operative to hold the material in flattened or extended condition throughout the succeeding cutting operations, and cutters
- 50 for operating on the material to produce blanks of various predetermined shapes.

55. In a machine of the character described, a table provided with a plurality of cutting blocks, means movable with each block for holding sheet material in flat-

tened or extended condition thereon, means for indicating the shape of the blank to be formed on each block, and cutters for operating on the material on the blocks to make blanks of a variety of shapes and in such an order that when assembled at an assembling station progressively with their arrival at that station complete articles are formed from said blanks.

56. In a machine of the character described, a table having blocks provided with perforations arranged in each block substantially in the outline of the blanks which will be cut from the material positioned on that block, said perforations serving as means to indicate to the operator the shape of the blank for each block, pointed members arranged to pass through the perforations and engage the material to hold it in proper position, cutters for operating on the material on the blocks, and members carried by the table for controlling the operation of the cutters whereby blanks of the desired shape are produced.

57. In a machine of the character described, a table having cutting blocks provided with perforations arranged in each block substantially in the outline of the blank which will be cut from the material positioned on that block, pointed members arranged to pass through the perforations and engage the material to hold it in proper position, cutters for operating on the material on the blocks, power means for operating the cutters comprising a clutch associated with each cutter, and members carried by the table in predetermined relation to each cutting block for controlling the operation of the clutches and thus determining the order of operations of the cutters by which blanks of various predetermined shapes are produced and in such an order that when assembled they form complete articles.

58. In a machine of the character described, a table having cutting blocks provided with perforations arranged in each block substantially in the outline of the blank which will be cut from the material positioned on that block, pointed members arranged to pass through the perforations and engage the material to hold it in proper position, cutters for operating on the material on the blocks, power means for operating the cutters comprising a clutch associated with each cutter, members carried by the table in predetermined relation to the cutting blocks for controlling the operation of the clutches and thus determining the order of operations of the cutters by which blanks of various predetermined shapes are produced and in such order that when assembled in succession they form complete articles, and an assembler for picking up the blanks from the blocks and com-

prising pointed members which enter the blanks from above before the first mentioned pointed members are withdrawn from below whereby the blanks are maintained in extended condition and accurately fitted to each other in the assembler to produce a complete article.

59. In a machine of the character described, a movable work supporting bed, a cutter for operating on work supported on the bed, power means for operating the cutter comprising a clutch, and means on the movable work supporting bed for controlling the clutch during movement of the bed.

15 60. In a machine of the character described, a movable work support, a cutter mounted to co-operate with the work support, a plunger for operating the cutter, a shaft for operating the plunger, and a clutch between the shaft and plunger arranged to be controlled by the movable work support.

25 61. In a machine of the character described, a work support, a cutter mounted to co-operate with the work support in cutting operations, a plunger for operating the cutter, a shaft having an eccentric, a pitman operated directly from the eccentric, a tilt-table member pivoted in the upper end of the plunger, and a link pivoted to the end of the pitman and slidable in the tilttable member for operatively connecting and disconnecting the pitman and plunger.

30 62. In a machine of the character described, a work support, a cutter mounted to co-operate with the work support in cutting operations, a plunger for operating the cutter, a shaft carrying an eccentric, a pitman operated from the eccentric, and a link connecting said pitman with the plunger 40 and shiftable operatively to connect or disconnect the pitman from the plunger.

63. In a machine of the character described, a rotatable work support having a plurality of cutting surfaces, a plurality of cutters arranged to co-operate with the cutting surfaces to cut blanks from sheet material, power means for operating the cutters comprising a clutch for each cutter by which it may be connected or disconnected from the power means, and means controlled by the table for determining the time of operation of each clutch and therefore of each cutter.

55 64. In a machine of the character described, a rotatable table having a plurality of cutting surfaces thereon, cutters mounted to co-operate with the cutting surfaces on the table, a die for operating upon material on all the cutting surfaces, and means 60 mounted on the table for causing the cutters to co-operate with certain of the cutting surfaces to the exclusion of others whereby blanks of different predetermined shapes are produced and collectable in such a man-

ner as to produce complete articles of the 65 shape desired.

65. In a machine of the character described, a work supporting table having a plurality of cutting surfaces, means for clamping the work upon the table over each 70 cutting surface while the same is at the operator's station, a cutter under the control of the operator for operating upon sheet material while it is at said station, and a plurality of cutters for operating on the 75 material after it has left said station to form blanks of various predetermined shapes.

66. In a machine of the character described, a work supporting table having a plurality of cutting surfaces, means for 80 clamping the work upon the table over each cutting surface while the same is at the operator's station, a cutter under the control of the operator for operating upon sheet material while it is at said station, a plurality 85 of cutters for operating on the material after it has left said station to form blanks of various predetermined shapes, and means for automatically operating the last mentioned cutters.

90 67. In a machine of the character described, a work supporting table having a plurality of cutting surfaces, a cutter normally out of operative relation to the work supporting surface so that the work may be 95 readily placed in position, a manually operable member for moving the cutter to operative position, power means for operating the cutter, and starting means for the power means arranged to be controlled by 100 the manually operable member upon continued movement of the same after the cutter is in operative position.

105 68. In a machine of the character described, a table having a plurality of work supporting surfaces, a plurality of cutters mounted to co-operate with said surfaces in cutting operations, means carried by the table for controlling the operation of the cutters so that a plurality of blanks of various 110 predetermined shapes are produced, an assembling means for picking the blanks from the table as the latter are presented in assembling position, and means carried by the table for controlling said assembling 115 means.

120 69. In a machine of the character described, a work supporting table, a plurality of cutters for co-operation with the table to cut blanks from sheet material positioned thereon, an assembler for picking up the blanks from the table in the order in which they are positioned in assembling position, and cam means carried by the table for controlling the operation of the cutters and of 125 the assembler so that blanks of various predetermined shapes are produced by the cutters and assembled by the assembler to

make complete articles of the desired shape.

70. In a machine of the character described, means for cutting pieces of leather into lift sections of various shapes, means for assembling the lift sections into complete lifts in superposed relation, a holder, and means for depositing the assembled lift sections in the holder.

71. In a machine of the character described, means for cutting pieces of leather into lift sections of various shapes, and means for automatically assembling the lift sections to make complete lifts arranged in superposed relation and for interposing a layer of cement between the surfaces of adjacent lifts to secure them together.

72. In a machine of the character described, means for cutting pieces of leather into lift sections of various shapes, means for automatically assembling certain of the lift sections to make a complete lift and for assembling other lift sections of different shapes from the first to produce a complete lift of the same shape as the first, a holder, and means for depositing the assembled lifts thus formed in said holder.

73. In a machine of the character described, means for cutting sheet material into blanks and for automatically assembling the blanks in predetermined relation to make a complete article, and means controlled by a dimensional characteristic of the assembled blanks for controlling the assembling means so that the latter discharges the assembled blanks when they have reached a predetermined dimension.

74. In a machine of the class described, means for cutting blanks from sheet material and for automatically assembling the blanks in superposed relation to produce a complete article, and means controlled by a thickness dimension of the assembled blanks for causing the assembling means to discharge the assembled blanks when they have reached a predetermined thickness.

75. In a machine of the character described, means for cutting blanks from sheet material of different shapes in predetermined order, means for automatically assembling the various blanks to make complete articles, and means for controlling the assembling means so as to discharge the articles when they have arrived at certain predetermined dimensions.

76. In a machine of the character described, means for cutting blanks from sheet material of different shapes automatically in predetermined order, means for assembling certain of the blanks to make an article and other blanks of different shapes to provide an article of the same shape as the first and superposed thereon, and means operable for securing the articles together.

77. In a machine of the character described, a table having a work supporting

surface, cutting means for cutting heel lift sections of different shapes from pieces of leather supported on said surface, an assembler for assembling lift sections to form complete lifts, cementing means, and means for operating the assembler to apply cement between adjacent surfaces only of the assembled lifts.

78. In a machine of the character described, a table having a work supporting surface, means for cutting heel lift sections of different shapes from pieces of leather supported on said surface, an assembler for assembling lift sections to form complete lifts, a holder for heels or heel sections, a cementing means located between the holder and the assembling position of the assembler, and means for operating the assembler to pick up lift sections from the table in such manner as to form complete lifts in superposed relation to each other and for moving the assembler so that cement is applied to the opposed surfaces only of the lifts and for causing the assembler to force the assembled lifts or heel sections into said heel holder.

79. In a machine of the character described, a table having work supporting surfaces, means for cutting heel lift sections of various shapes from pieces of leather supported on said surfaces, an assembler co-operating with the table for assembling lifts and lift sections from the table to form complete lifts in superposed layers, cementing means for applying cement between adjacent surfaces of the lifts and pieced lifts thus forming heels or heel sections, and means controlled by the thickness of the heel section thus assembled in the assembler for causing the assembler to eject the heel section.

80. In a machine of the character described, a table having work supporting surfaces, means for cutting heel lift sections of various shapes from pieces of leather supported on said surfaces, an assembler for assembling lift sections from the table to form complete lifts in superposed layers, means operable for securing the layers together, and means controlled by the thickness of the heel section thus assembled in the assembler for causing the assembler to eject the heel section, said last named means being adjustable so that heel sections of various predetermined thickness may be formed and automatically ejected from the assembler.

81. In a machine of the class described, a movable table having a work supporting surface, a die for cutting a blank from sheet material positioned on said surface, cutters for successively operating on the blank as the table is moved to position said blank successively in co-operative relation with the cutters, power operating means, starting means for the machine, and a manually oper-

able member for positioning the die and for controlling the starting means.

82. In a machine of the class described, a table having a plurality of work supporting surfaces, a die for successively cutting blanks from sheet material supported on each of said surfaces, a plurality of cutters arranged to co-operate with said work supporting surfaces and to be controlled by the table for cutting the blanks after they have been operated upon by the die, power operating means, starting means for the machine, and a manually operable member for controlling the die and for actuating the starting means.

83. In a machine of the class described, a rotatable table having a plurality of work supporting surfaces, a die for successively operating upon sheet material supported on said surfaces, a plurality of cutters for operating on the blanks cut by the die, cam blocks carried by the table for controlling the operation of said cutters, power means for operating the machine, starting means, and a manually operable member for moving the die to operative position and for controlling the starting means.

84. In a machine of the character described, a table provided with a plurality of cutting blocks upon which the work is supported during cutting operations, each block being provided with perforations, a plurality of members arranged to pass through the perforations and having sharpened ends designed to penetrate the material positioned on the block to hold the material in proper position, cutters for operating on the material to cut blanks therefrom, and means automatically operative to sweep waste pieces away from the blanks and off the table.

85. In a machine of the character described, a table provided with a work supporting surface, means operative through the table from below for holding the sheet material in flattened or extended condition thereon, cutters for operating on the material to make blanks therefrom, and means for sweeping the waste pieces away from the blanks held by said holding means.

86. In a machine of the character described, a table having a work supporting surface, pins operative through the table from below to penetrate work and hold it in proper position, cutters for operating on the material held by the pins, and a sweep for removing the waste pieces away from the blanks held by the pins.

87. In a machine of the character described, a die for operating on pieces of leather to produce the permanent peripheral contour lines of lift sections, and a plurality of cutters automatically operative to make cuts which intersect the said contour lines of the lift sections.

88. In a machine of the character de-

scribed, a movable work supporting table, means for holding sheet material on the table, cutters for operating on the material to cut blanks therefrom, an assembler comprising a plurality of penetrating members arranged to enter each blank before the holding means is released, means for operating the assembler intermittently in timed relation with the movements of the table to pick up blanks successively from the table and hold them in assembled relation, and means for operating the assembler to cause the discharge of the assembled lifts when they have reached a predetermined thickness.

89. In a machine of the character described, a movable work supporting table, means for holding sheet material on the table, cutters for operating on the material to cut blanks therefrom, an assembler comprising a plurality of penetrating members arranged to enter each blank before the holding means is released, means for operating the assembler intermittently in timed relation with the movements of the table to pick up blanks successively from the table and hold them in assembled relation, and means co-operating with the assembler to secure the layers of lifts together in the assembler before the discharge of the heel or heel sections thus formed.

90. In a machine of the character described, a movable work supporting table, means for holding sheet material on the table, cutters for operating on the material to cut blanks therefrom, an assembler comprising a plurality of penetrating members arranged to enter each blank before the holding means is released, means for operating the assembler intermittently in timed relation with the movements of the table to pick up blanks successively from the table and hold them in assembled relation, a cementing means, and means for operating the assembler to apply cement between the layers of blanks whereby the layers are held together to make a complete article.

91. In a machine of the character described, a table provided with a plurality of cutting blocks, means for indicating the shape and the size of the blank to be formed on each block, and cutters for operating on the material on the blocks to make blanks of the various predetermined shapes indicated by the indicating means.

92. In a machine of the character described, a table provided with a plurality of spaced cutting surfaces, means for indicating the shape and size of the blank that will be formed on each cutting surface, means for holding the material on the cutting surfaces during cutting operations, cutters for operating on the material on the cutting surfaces to make blanks of various predetermined shapes, the cutters being arranged to produce blanks in groups wherein the blanks

have a predetermined relation to each other, and an assembler, the construction and arrangement being such that the assembler and the table co-operate to assemble the blanks to 5 make complete articles.

93. In a machine of the character described, a work supporting bed, a plurality of tools for operating on work supported on the bed, power means for operating the tools 10 comprising clutches for operatively connecting each tool with said power means, and means on the work support for controlling the clutches to determine the time of operation of each tool.

15 94. In a machine of the character described, a movable work support, a tool mounted to co-operate with the work support, a plunger for operating the tool, a shaft for operating the plunger, and a clutch 20 between the shaft and plunger arranged to be controlled by the work support during movement of the latter.

95. In a machine of the character described, means for cutting pieces of leather 25 into lift sections of various shapes, means for assembling the lift sections to form complete lifts, a holder, and means for depositing the assembled lift sections in the holder.

96. In a machine of the character described, means for cutting from sheet material blanks of different shapes, and means 30 for assembling certain of the blanks to make a complete article and other blanks of different shapes from those last mentioned to 35 produce another article of the same shape as the first.

97. In a machine of the character described, a work support, means for cutting pieces of leather positioned on the support 40 into lift sections of various shapes, and means for assembling the lift sections into complete lifts.

98. In a machine of the character described, means for cutting pieces of leather 45 into lift sections, means for assembling the lift sections into complete lifts, a holder, and means for successively depositing the assembled lift sections in the holder.

99. In a machine of the character described, means for assembling blanks of different shapes in predetermined order to 50 make complete articles, and means for controlling the assembling means so as to discharge the articles when each has arrived at 55 a certain predetermined dimension.

100. In a machine of the character described, means for assembling blanks of different shapes in predetermined order to 60 make complete articles, and means for controlling the assembling means to discontinue the assembling of blanks when the latter have been assembled and attained a certain predetermined dimension.

101. In a machine of the character described, a die for operating on pieces of 65

leather to produce the permanent peripheral contour lines of lift sections, a support for pieces of leather, and a plurality of cutters for operating on the pieces of leather carried by said support to make cuts which intersect the contour lines of the lift sections produced by the cutting edges of the die in the dieing operation. 70

102. In a machine of the character described, a die for operating on pieces of 75 leather to produce the permanent peripheral contour lines of lift sections, a support for the pieces of leather, and a plurality of cutters operable to straight edge the lift pieces cut by the die to produce complementary lift 80 sections which may be assembled into complete lifts.

103. In a machine of the character described, means for cutting heel lifts from sheet material comprising cutters and a support for the material, means for assembling 85 a predetermined number of the lifts from the support to make a heel or heel section, and means for pasting each lift after it is cut so that the assembled lifts are secured 90 together, the construction and arrangement being such that no paste is applied to the exposed surface of the top lift.

104. In a machine of the class described, an assembler for heel lifts, a pasting device 95 for applying paste to the opposed surfaces of the lifts whereby the lifts are secured together to form a heel or heel section, a holder for the heels or heel sections, and means for ejecting the assembled lifts from the 100 assembler and forcing them into the holder.

105. In a machine of the class described, an assembler having a plurality of pointed members distributed so as to engage different pieces of sheet material when presented 105 in different positions, means for causing pieces to be impaled upon the pointed members in side by side relation, and means for securing pieces together in superposed relation to form a composite article. 110

106. In a machine of the class described, an assembler for heel lifts comprising a plurality of pointed members, means for impaling lifts upon the pointed members to produce heels or heel sections, and means for moving the assembler to a position where the heels or heel sections are discharged by the assembler. 115

107. In a machine of the class described, a movable assembler for heel lifts comprising a plurality of pointed members, means for impaling the lifts upon the pointed members, and means for ejecting the assembled lifts from the assembler at a discharge station. 120

108. In a machine of the class described, a plurality of supports for pieces of material, an assembler comprising pointed members upon which pieces of material are successively impaled in side by side and in su- 130

perposed relation so as to produce composite articles, means for securing the pieces together, and means for discharging the articles from the assembler.

- 5 109. In a machine of the class described, a plurality of supports for pieces of material, an assembler movable between collecting and discharge stations comprising a pointed member upon which pieces of material from different supports are successively impaled so as to produce a composite article, and means for ejecting the pieces from the pointed member at the discharge station.
- 10 110. In a machine of the class described, 15 a plurality of supports for pieces of material, a plurality of assemblers each comprising a pointed member upon which the pieces of stock may be impaled, means for causing relative movement between the supports and the assemblers, so that pieces of stock from different supports may be impaled upon the pointed member of each assembler, means for impaling the pieces of stock on the pointed members, and means for securing 20 the pieces of stock together to form composite articles.
- 25 111. In a machine for making heels or heel sections, a plurality of supports for lifts, a plurality of assemblers each comprising a pointed member, a carrier for supporting and moving the assemblers along a curved path, means for impaling the lifts upon the pointed members, and means for securing the lifts together to make heels or 30 heel sections.

- 35 112. In a machine for making heels or heel sections, a plurality of supports for lifts, a plurality of assemblers each comprising a pointed member upon which the lifts may be impaled, a carrier for supporting the assemblers and moving them step-by-step into co-operative relation to the supports for the lifts, means for impaling a plurality of lifts upon each pointed member progressively to build up heels or heel sections, and means for ejecting the heels or heel sections at a discharge station.

- 40 113. In a machine for building heels or heel sections, a plurality of supports for lifts, a plurality of assemblers each comprising a pointed member upon which lifts are assembled to produce a heel or heel section, means for causing relative movement between the assemblers and the supports to bring the assemblers into lift receiving positions, means for forcing the lifts progressively upon the pointed members in the assemblers, and means for securing the lifts together prior to their discharge from the assemblers.

- 45 114. In a machine of the class described, a plurality of supports for pieces of material, an assembler for receiving the pieces and holding them in predetermined relation to each other, means for causing relative

movement between the assembler and the supports to bring the assembler into piece-receiving position, and means associated with the supports for controlling the last-mentioned means.

- 50 115. In a machine of the class described, a plurality of supports for pieces of material, an assembler movable relatively to the supports to take pieces therefrom and assemble them in predetermined relation to each other to form articles, a holder in which the articles are deposited by the assembler, and a plurality of members associated with certain of the supports for controlling the operations of the assembler.

- 55 116. In a machine of the class described, a plurality of supports for pieces of material, an assembler movable relatively to the supports to pick up therefrom pieces of material to form composite articles composed of pieces of different shapes for the articles successively assembled, means for applying paste to the articles after each is assembled, and means associated with the supports for controlling the relative movements of the assembler, the pasting means and the supports.

- 60 117. In a machine of the class described, an assembler having a plurality of pointed members distributed so as to engage pieces of material and hold them with their edges in abutting relation, means for causing the pieces to be impaled upon the pointed members, and means for securing the pieces together in the described abutting relation whereby a single composite article is produced.

- 65 118. In a machine of the class described, an assembler for pieced heel lifts comprising a plurality of pointed members distributed to engage pieces of different shapes which compose the lift, means for impaling the pieces upon the pointed members, and means for moving the assembler to a position where the lift is deposited by the assembler.

- 70 119. In a machine of the class described, an assembler for pieced heel lifts comprising a plurality of pointed members distributed to engage pieces of material and hold them with their edges abutting as in the completed lift, means for impaling the pieces upon the pointed members, a holder for lifts, and means for moving the assembler into position over the holder and for discharging the assembled lift into said holder.

- 75 120. In a machine of the class described, a supporting means for pieces of material, an assembler comprising pointed members upon which lift sections are successively impaled in side by side relation upon relative movement between the assembler and the supporting means so as to produce a complete lift, means for securing a plurality of lifts together while they are on the pointed

- members, and means for discharging the heel or heel section thus formed from the assembler.
121. In a machine of the class described, 5 a supporting means for pieces of material, an assembler comprising a pointed member upon which pieces of material are successively impaled so as to produce a composite article, and means for applying cement between the pieces on the pointed member so as to produce composite articles.
122. In a machine of the class described, 10 means for supporting pieces of material, a plurality of assemblers each comprising a pointed member upon which the pieces of stock may be impaled, means for causing relative movement between the supporting means and a pointed member in each assembler for forcing the pieces of stock on 15 the assemblers, and means for securing the pieces of stock together to form composite articles.
123. In a machine for making heels or heel sections, supporting means for lift sections, 15 an assembler comprising a plurality of pointed members, means for impaling lift sections upon the pointed members to produce a plurality of lifts assembled in superposed relation, and means for applying paste between the assembled lifts to secure the latter together to make a heel or heel section.
124. In a machine for making heels or heel sections, supporting means for lifts, a plurality of assemblers comprising pointed 20 members upon which the lifts may be impaled, means for impaling a plurality of lifts upon the pointed members progressively to build up heels or heel sections, and means for discharging the assembled lifts 25 from the assemblers.
125. In a machine for building heels or heel sections, supporting means for lifts, a plurality of assemblers each comprising a plurality of pointed members upon which 30 lifts are assembled to produce a heel or heel section, means for causing relative movement between the assemblers and the supporting means to bring the assemblers into lift receiving positions, means for forcing 35 the lifts progressively on to the pointed members in the assemblers, and means for securing the lifts together prior to their discharge from the assemblers.
126. In a machine of the class described, 40 supporting means for pieces of material, an assembler comprising a pointed member for receiving the pieces and holding them in predetermined relation to each other, means for causing relative movement between the assembler and the supporting means to force the pieces into the assembler, and means on the supporting means for controlling the last-mentioned means.
127. In a machine of the class described, 45 supporting means for pieces of material, an assembler movable relatively to the supporting means to take pieces therefrom and assemble them in predetermined edge to edge relation to each other to form articles, a holder in which the articles are deposited by the assembler, and means associated with the supporting means for controlling the operations of the assembler.
128. In a machine of the class described, 50 a support for pieces of material, an assembler movable relatively to the support to pick up therefrom pieces of material to form composite articles composed of different shapes and numbers of pieces, the arrangement being such that the relative movement between the assembler and the support varies in each cycle with the number of pieces necessary to complete the article and means associated with the support for controlling the relative movements of the assembler and the support.
129. In a machine of the class described, 55 a transerrer constructed to pick up a plurality of pieces of stock in edge abutting relation, and a holder or receiving member into which the transerrer forces the stock upon relative approaching movement of the transerrer and holder.
130. In a machine for operating on sheet material, a member provided with pointed devices adapted to penetrate the material for holding pieces thereof in extended condition after the material has been pressed thereon and the pressure removed, and a cutting device which operates on the material presented by said member.
131. In a heel building machine, means for supporting a plurality of lifts, means comprising a pointed member for successively operating on the lifts from above for lifting the same from the supporting means and assembling them in a pile of predetermined height, a stripper plate through which the pointed member normally projects, said stripper plate being moved upwardly as lifts are forced on the pointed member, and ejector means controlled by the stripper plate to determine the time of operation of the latter.
132. A heel building machine, having, in combination, a movable carrier having a plurality of pointed members, means for forcing heel stock on said pointed members whereby it is retained on the carrier, a stock stripping plate associated with the carrier, means for operating said carrier from the stock receiving station to a discharge station, and means for causing the stripping plate to remain stationary while the pointed members are withdrawn to remove the stock from the latter.
133. A heel building machine, having, in combination, means for cutting pieces from sheet material comprising a die, a plurality of cutters automatically operative to straight

- edge pieces cut by the die, a plurality of pointed members, means for positioning the straight edged pieces beneath the pointed members, means for impaling said pieces upon the pointed members, and means for securing the pieces together to form an article.
134. A heel building machine, having, in combination, a manually controllable die for cutting pieces from sheet material, a plurality of cutters for operating automatically on the pieces cut by the die, a plurality of pointed members, means for impaling said pieces upon the pointed members, and means for securing the pieces together to produce a composite article.
135. A heel building machine, having, in combination, means for cutting pieces from sheet material, a plurality of pointed members, means for transferring the cut pieces into position beneath the pointed members, means for impaling said pieces upon the pointed members, and means for moving the pointed members to transfer the pieces from the station where they were received upon the pointed members to a discharge station.
136. A heel building machine, having, in combination, a cutter for cutting pieces from sheet material, a pointed member, means for impaling said pieces upon the pointed member, and means for moving the pointed member to transfer the pieces from the station where they were received upon the pointed member to a discharge station.
137. A heel building machine, having, in combination, a support for pieces of sheet material, a plate having a pointed member and adapted to be moved from a piece-receiving position with respect to said support to a discharging position, means for impaling a piece of sheet material upon said pointed member, and means comprising a stripper plate on the pointed member for effecting the discharge of the piece upon said pointed member at a time when it occupies its discharging position.
138. A heel building machine, having, in combination a manually controllable power-operated die for cutting pieces from sheet material, a plurality of cutters for operating selectively and automatically on the pieces cut by the die, a plurality of pointed members, means for transferring the cut pieces into position beneath the pointed members, means for impaling said pieces upon the pointed members, and means for securing the pieces together to form an article.
139. A heel building machine, having, in combination, a heel carrier comprising a pointed member rigidly secured therein, means for actuating the carrier step-by-step through a plurality of stations including a heel or heel section pressing station, means for successively impaling a plurality of lifts on the pointed member, and devices controlled by the height of the heel or heel sec-
- tion while still on the pointed member for determining when the heel or heel section is to be pressed.
140. A heel building machine having, in combination, a heel carrier comprising a plurality of pointed members rigidly secured therein, means for successively impaling a plurality of lifts on said pointed members, heel or heel section pressing means, means for actuating the carrier to advance it to the heel pressing means, and means controlled by the height of the heel or heel section on the pointed members for effecting the heel pressing operation.
141. A heel building machine having, in combination, a heel building device comprising a plurality of pointed members which project from its heel holding face, movable means for positioning a plurality of lift sections in a location opposite to the heel holding face of the device, and mechanism for causing periodic relative movements between said means and device successively to impale the lift sections on the pointed members in side by side and in superposed relation to form a heel or heel section.
142. A heel building machine having, in combination, a heel building device comprising a plurality of pointed members upon which lift sections may be impaled, means for impaling lift sections successively on said member in face to face and side by side relation to build a heel or heel section, and means for ejecting the completed article.
143. A heel building machine having, in combination, a heel building device comprising a plurality of pointed members upon which lifts may be impaled, means for impaling lifts successively on the pointed members in face to face relation when building a heel or heel section, and means for measuring the height of the article thus produced and ejecting it at a predetermined height.
144. A heel building machine having, in combination, a heel building device comprising a plurality of pointed members upon which lift sections may be impaled, means for impaling lift sections successively on the pointed members in face to face and side by side relation to build a heel or heel section, and means for applying paste between the lifts to secure them together and form a heel or heel section.
145. A heel building machine having, in combination, a movable lift carrier adapted to occupy a lift receiving station and a heel delivering station, said carrier comprising a plurality of pointed members rigidly secured therein, means for successively moving lifts laterally to a position beneath the carrier, means for causing relative movement between the carrier and the first mentioned means to impale lifts on the pointed members whereby they are secured in superposed relation on the under side of the carrier,

- means for pasting the under sides of the lifts, and means for discharging the heel thus assembled from the carrier at the delivering station.
- 5 146. A heel building machine having, in combination, a movable carrier adapted to occupy a station in which a lift is first positioned beneath it, said carrier comprising a plurality of pointed members rigidly secured therein and projecting downwardly from the under side of the carrier, and means for impaling lifts upon the pointed members and for applying paste to the exposed face only of each lift as it is sustained by the 15 carrier.
147. A heel building machine having, in combination, a heel building device adapted to receive and sustain a plurality of lifts comprising a plurality of pointed members 20 rigidly secured in the device and upon which the lifts are impaled, means for successively positioning lifts beneath the device, and means for impaling the lifts successively in a superposed pile upon the pointed members 25 on the under side of the device and applying paste to one of the two contacting surfaces of adjacent lifts in the pile.
148. A heel building machine having, in combination, a heel carrier comprising a plurality of pointed members projecting downwardly from the under surface of the carrier, means for successively positioning lift sections beneath the carrier and for impaling the lift sections upon the pointed 30 members, and means for moving the carrier to a delivering station.
149. A machine for building heels or heel sections comprising a holder of a length to accommodate a plurality of heels or heel 35 sections, and a plurality of means operating in succession to cut and paste lifts, assemble them into heels and heel sections and deposit them in the holder.
150. A machine for building heels or heel 40 sections comprising a holder of a length to accommodate a plurality of heels or heel sections, lift cutting and assembling means operative in succession to cut and assemble lifts into heels or heel sections, and means 45 for ejecting each heel or heel section after it is formed into said holder.
151. A machine for building heels or heel 50 sections comprising a holder of a length to accommodate a plurality of heels or heel
- sections, and a plurality of means operating in succession to cut lifts, paste them together and then deposit them in the holder.
152. In a machine of the class described, a holder for lifts, and means for cutting lifts, securing them together with cement, and then placing them in the holder.
153. In a machine of the class described, a holder for lifts, means for cutting pieces of material into lift sections, and means for assembling the lift sections into lifts and 65 depositing them in the holder in assembled relation.
154. In a machine for building heels or heel sections, comprising a holder of a length to accommodate a plurality of heels or heel 70 sections, means for cutting whole lifts and lift sections from sheet material, means for assembling whole lifts and lift sections to form heels or heel sections, and means for depositing them in the holder.
155. In a machine of the character described, means for cutting from sheet material lift sections of different shapes in a pre-determined order so that when assembled in order complete lifts will be formed, and 80 means for assembling the lifts and securing them together to form heels or heel sections.
156. A heel building machine having, in combination, a support for heel stock, cutters for cutting the stock into lifts and lift sections, and means for impaling and securing together the lifts and lift sections at an assembling station, removing them from the support and discharging them at a receiving 85 station in the form of a heel.
157. A heel building machine having, in combination, a support for heel stock, cutting means for operating on stock on the support to produce lifts, and means for impaling and securing together the lifts at an assembling station, removing them from the support and discharging them at a receiving 90 station in the form of a heel.
158. In a heel making machine, the combination of lift cutting mechanism, lift assembling mechanism, a blank receiving magazine, and means for removing a blank from the assembling mechanism and inserting it in the magazine.

In testimony whereof I have signed my name to this specification.

FRED ASHWORTH.
